UNITED STATES PATENT OFFICE.

NORDAL MIKELSON, OF MECKLING, SOUTH DAKOTA.

CORN-HUSKING MACHINE.

1,274,432.

Specification of Letters Patent. Patented Aug. 6, 1918.

Application filed September 10, 1915. Serial No. 50,067.

To all whom it may concern:

Be it known that I, NORDAL MIKELSON, a citizen of the United States, residing at Meckling, in the county of Clay and State 5 of South Dakota, have invented certain new and useful Improvements in Corn-Husking Machines, of which the following is a specification.

My invention relates to corn husking machines and contemplates an improvement in the construction, combination and arrangement of the component parts thereof.

In the drawings, annexed:

Figure 1 is a side elevation of my improved corn husking machine;

Fig. 2 is a top plan view, the feed conveyer having been removed;

Fig. 3 is a cross sectional view;

Fig. 4 is an enlarged cross sectional view 20 illustrating the means by which the husking rolls are held in contacting relation;

Fig. 5 is a fragmentary view, in elevation, further illustrating the part shown in Fig. 4;

Fig. 6 is a detail cross sectional view of 25 one of the husking rolls; and

Fig. 7 is a detail longitudinal sectional view illustrating the manner in which the husking pins are mounted.

Like numerals of reference designate like 30 or corresponding parts throughout the several views.

Coming now to a detail description of the machine, 1 designates the main frame of the machine and 2 an auxiliary frame supported in spaced relation thereabove through the medium of supporting brackets 3. The main frame 1 is mounted on supporting wheels 4 and is adapted to be drawn along behind a wagon 5 into which the elevated 35 end of a conveyer designated as an entirety by the numeral 6 discharges. Any suitable means such as a draft tongue 7 may be utilized to fasten the wheeled supporting frame or the corn husking machine to the wagon 5.

40 A trough like inclined hopper 8 is mounted above the main frame 1 and the auxiliary frame 2, standards or uprights 9 affording a support means for the hopper sides. A deflector plate 10 is fastened in any suitable manner to one of the hopper sides that the corn directed or thrown in the general direction of the hopper may be deflected and consequently directed thereto.

45 A suitable feed conveyer 11 is mounted to operate at the base of the hopper to convey 50 the corn directed thereto upwardly at an

inclination and to an opening 10' formed in the hopper base at the elevated end thereof.

Beneath the hopper 8 is arranged a secondary hopper 12 the sides of which engage with the uprights or standards 9 that the hopper as an entirety may be held or supported against movement.

55 Husking rolls 13 and 14 are mounted to extend longitudinally of the hopper 12 and in parallelism, one of said rolls being directly driven in the manner hereinafter fully described and the other of said rolls, by reason of its engagement with the roll 70 first mentioned, rotating in a counter-direction. Roll 13 is mounted on a shaft 15 journaled in the machine frame 2. A bevel gear 16 is mounted at one end of the said shaft 15 to mesh with a like gear 17 mounted 75 on a shaft 18 journaled in brackets 19 fastened to the rear end of the auxiliary frame 2.

The shaft 18 carries a sprocket 20 over which a chain 21 operates to drive a second 80 sprocket 22 mounted on a shaft 23 journaled in bearings 24 secured to the main frame 1. The shaft 23 is driven to operate the conveyer 6 which, as shown to advantage in Figs. 2 and 3 is located at one side of the 85 main frame and within a conveyer frame 25 therefor. Said conveyer 6 is mounted to operate at an angle or inclination to convey husked corn upwardly to a point of discharge directly above the wagon box or 90 container 5.

95 Shaft 18 is equipped at one end with a pulley 26 over which a belt 27 operates, the said belt being crossed and driven through the medium of a pulley 28 in turn driven by an engine 29 (preferably of the internal combustion type) mounted on the main frame 1.

Said shaft 18 is further equipped with a 100 sprocket 30 over which a chain 31 operates, the said chain engaging with a sprocket 32 on a shaft 33 that the feed conveyer 11 may be driven as hereinbefore stated. By the above arrangement it is evident that the feed conveyer 11, the husking rolls 13 and 14, the conveyer 6 and a reciprocatory shuttle board or blade 34 (subsequently to be described) are all driven by the engine 29.

105 Upon the opposite end of the shaft 15 from that supporting the bevel gear 16 is mounted a like bevel gear 35, this last mentioned gear being in mesh with a bevel gear

36 mounted on a shaft 37 journaled in brackets 38 secured to the auxiliary frame 2. Said shaft 37 is provided with a crank terminal 39 over which one end of a reciprocating rod 40 is mounted, the said rod receiving its reciprocating movement by reason of its engagement with the crank terminal 39 just mentioned. Said rod 40 at its opposite end is in engagement with 10 a fulcrumed or rocking arm 41 pivoted as at 42 in an opening therefor of the frame 2. Said arm at its opposite end is pivotally connected as at 43 to the shuttle board or blade 34 that the latter may be reciprocated 15 through rotation of shaft 27. A link 44 is pivoted at one end to the shuttle 34 and its opposite end to the auxiliary frame that the former, shuttle 34, may be properly supported and held in a position directly above 20 the husking rolls whereby to dispose the serrated or toothed edge 45 thereof in engagement with the corn acted on.

Shaft 15, at a point in proximity to the gear 35 mounts a sprocket 46 over which a 25 chain 47 operates to drive a sprocket 48 mounted on a shaft 49 extending in parallelism with the shaft 15 thereabove. Said shaft carries at its opposite end what may be termed a kicker-disk 49 from which a 30 pin 50 projects, the said pin being rotatable to engage with and elevate or throw the husked corn that the ears may be directed through an opening 51 in the hopper 12. A chute 52 is arranged over the opening 51 35 to convey the husked corn to the elevator or conveyer 6 previously described.

Husking roll 14, or rather the shaft 53 which acts as a support therefor is mounted to move relatively to the auxiliary frame 40 that the roll 14 may be held in yielding contact with the roll 13 which is rigid. A pressure roll 54, spring pressed as indicated at 55 is mounted to engage with the roll 14 to thus hold the two husking rolls in yielding contact or in engaging proximity. This arrangement will permit relative movement of the roll 14 should the machine for any reason fail to remove the husks and cause an ear of corn to be forced between the husking rolls. Such arrangement will preclude breakage under normal operating conditions.

Each husking roll is equipped with a plurality of transversely extending hollow pin tubes 56, the mentioned tubes being exteriorly threaded at one end or as indicated at 57 to engage with the roll itself. Said tubes are thus held in place. Within each tube 56 thus mounted is disposed a husking 60 pin 58, the said pin being adapted for movement relatively to the tube 56, such movement being against tension of a spring 59 located interiorly of the tube and abutting at one end a stop pin 60 and at its opposite

end a transverse pin 61 carried by the husking pins 58. Each of the several husking pins thus mounted project radially from the periphery of the husking rolls and during engagement of one roll with the other recede to permit proper rotation of the mentioned 70 rolls without relative bodily movement.

In operation, and as before suggested, the corn acted on is thrown into the hopper 8 and through operation of the feed conveyer 11 directed to the opening 10' in said hopper. 75 From the opening 10' the corn is directed to the hopper 12 and against the husking rolls. The mentioned rolls being set to operate at an inclination it is apparent that the corn or ears will gravitate toward the lower end of 80 said rolls, and through operation of the husking pins 58 and the shuttle 34, is so treated or acted on as to cause the husks to be entirely removed. The removed husks will fall or gravitate to a point below the 85 husking rolls where they may be collected in any suitable manner. The husked corn, finally reaching the lower end of the husking rolls, will be engaged by the kicker-pin 50 and through such engagement directed to 90 the opening 51 and thence by the chute 52 to the conveyer 6. From the conveyer the husked corn is carried upwardly and into the wagon box or container 5.

I am aware that corn husking machines 95 have been heretofore provided embodying shuttles mounted for movement adjacent the husking rollers, but to my knowledge in each instance the shuttles have been mounted for movement in a plane at right-angles to the 100 plane of inclination of the husking rollers and not in a plane parallel to the plane of inclination of the rollers, as in the machine of my invention described above. Owing to this arrangement, that is the mounting of the shuttle for movement in a plane parallel to the inclination of the shuttle of the husking rollers, the ears of corn, after being partly rotated by movement of the husking rollers, in the usual manner, are engaged by the shuttle, thereby slightly dislodging the ears so as to rotate them slightly to permit the studs of the husking rollers to engage other portions of the husks whereby to effectively remove the husks before the ears 115 arrive at the lower end of the machine. The ears are thus subjected to a slight rolling motion by the engagement therewith of the shuttle tending to force the ears from the rollers, which tendency is offset by the rotation of the rollers to maintain the ear in a position between the rollers. In machines of the character heretofore provided wherein the shuttles are mounted for movement toward the juncture of the rollers, the ears 120 will be forced therebetween and not subjected to the rolling motion desirable to insure the removal of all the husks.

From the foregoing, taken in connection with the accompanying drawings it is apparent that the several mechanisms involved may all operate, and operate properly, 5 through the agency of a single engine or other power means; that the various component parts are so arranged relatively to the supporting frame 1 as to occupy a minimum of space and permit of access should 10 repair make such access necessary; and that the shuttle, by reason of its location above the husking rolls will contact with the ears of corn and to a material extent loosen the husks that they may be later removed by the 15 husking pins 58.

In reduction to practice, I have found that the form of my invention, illustrated in the drawings and referred to in the above description, as the preferred embodiment, is 20 the most efficient and practical; yet realizing that the conditions concurrent with the adoption of my device will necessarily vary, I desire to emphasize the fact that various minor changes in details of construction, 25 proportion and arrangement of parts may be resorted to, when required, without sacrific-

ing any of the advantages of my invention, as defined in the appended claim.

Having thus fully described my invention, what I claim as new and desire to secure by 30 Letters Patent, is:—

In a corn husking machine, the combination of a frame, a pair of inclined husking rollers in horizontally spaced relation, a reciprocable shuttle in the form of a flat bar 35 disposed upon the rollers in parallelism thereto and having one longitudinal edge serrated and said edge located above the space between the rollers, a pair of links pivotally mounted at one of their ends upon the frame for supporting the shuttle upon their opposite ends, means for vibrating said shuttle across the upper face of said rollers and in a plane parallel to the plane of the inclination thereof. 40

45 In testimony whereof I affix my signature in presence of two witnesses.

NORDAL MIKELSON.
